PNEUMATIC TOOL

1,152,624.

Specification of Letters Patent.

Patented Sept. 7, 1915.

Application filed January 2, 1908. Serial No. 408,877.

To all whom it may concern:

Be it known that I, GEORGE H. GILMAN, a citizen of the United States, residing at Claremont, in the county of Sullivan, State of New Hampshire, have invented an Improvement in Pneumatic Tools, of which the following description, in connection with the accompanying drawings, is a specification, like letters on the drawings representing like parts.

My invention relates to pneumatic or other pressure-fluid actuated tools, being more particularly intended to provide a tool having two or more tool-actuating units together with suitable means for controlling or regulating the operation of said units.

While my invention in its broader aspects may be embodied in constructions other than the one herein shown, in the illustrated embodiment thereof the same is disclosed as applied to a duplex tool of the pneumatic piston-hammer type.

I have also shown the same as more particularly intended for employment in connection with the surfacing or dressing of stone, but this is merely one application which may be made of my invention, and the latter is in no broad sense restricted to this particular use.

My invention will be best understood by reference to the following description when taken in connection with the accompanying illustration of one specific embodiment thereof, while its scope will be more particularly pointed out in the appended claims.

In the drawings: Figure 1 is a central, sectional elevation taken through the working cylinders and controlling valve of a duplex hammer-tool embodying one form of my invention; Fig. 2 is a similar section taken in a plane at right-angles to the view shown in Fig. 1; Fig. 3 is a detail showing the regulating valve in a position different from that in Fig. 1; Fig. 4 is another detail showing the regulating valve in a third position; Fig. 5 is a plan in section taken on the line 5—5 in Fig. 1; Fig. 6 is a section in plan taken through the working cylinders on the line 6—6 in Figs. 1 and 2; Fig. 7 is a sectional elevation taken through the valve and valve block on the line 7—7 in Figs. 1 and 5; Fig. 8 is a detail showing the regulating valve with a portion of the valve stem attached; Fig. 9 is a section on the line 9—9

in Fig. 8; Fig. 10 is a section on the line 10—10 in Fig. 8; Fig. 11 is a section on the line 11—11 in Fig. 8; Fig. 12 is a general diagrammatic view showing a development of the pressure passages relatively to the controlling and regulating valves; Fig. 13 shows the controlling valve in a reverse position from that shown in Fig. 12; Fig. 14 shows the regulating valve in a different position from that shown in Fig. 12 and corresponding to the position shown in Fig. 4; Fig. 15 shows the regulating valve in a third position and corresponding to the position shown in Fig. 3; Fig. 16 is a partial side elevation of the duplex tool shown in Fig. 1 showing the regulating valve handle; Fig. 17 is a sectional elevation taken through the swivel support for the hammer tool; and Fig. 18 shows the disposition of the tool relatively to the support when employed upon a stone surfacing machine.

Referring to the drawings and to the illustrated embodiment of my invention, I have shown the same as applied to a pneumatic tool of the piston-hammer type provided with a pair of working cylinders with their cooperating and contained hammer-pistons arranged side by side. Any desired arrangement or construction of the cylinders and pistons may be employed, but in the drawings (Fig. 1) the cylinder chambers 1 and 2 are shown as formed within a single cylinder casting 3, the latter being provided with the upper head 4 closing the upper or head-end of the cylinder and the lower head 5 secured to the lower end thereof. The pistons 6 and 7, which may be of any desired construction, are shown as provided with reduced striking or hammer ends which, as they reciprocate, are adapted to strike the ends of independent and separate tools 8 and 9 loosely held within the bushings 10 and 11. In a duplex or multiplex tool of this kind, and particularly where such tool is to be employed as a hand tool, it is desirable to reduce the shock to be sustained by the tool structure, which shock would ordinarily be increased with the number of tool-actuating units, were the latter to reciprocate in step and strike their tools simultaneously.

By the present invention I have arranged the hammer-pistons to reciprocate non-synchronously or out of step so as to reduce

such shock and vibration, and, in the illustrated embodiment of the invention, the said pistons are arranged to move in opposed step, whereby shock due to the downward movement of one is largely neutralized by the upward movement of the other and vice versa, so that the resultant operation of the duplex tool is accompanied by even less vibration and shock than the operation of the single tool.

While separate valves may be employed for the two tool units, or any other suitable arrangement of controlling device provided, as the simplest and most effective way of controlling the movements of the piston-hammers, I preferably provide valve means common to the two working cylinders, the operation of such valve means providing for a movement of one hammer-piston in one direction as the other simultaneously executes a movement in the opposite direction. Any suitable construction of valve may be used, but as shown there is employed a differential pressure-actuated valve located within the valve block 12, the latter formed in the upper part of the cylinder head 4, and, in turn, surmounted by the endpiece 13, the latter containing the pressure fluid admission passage 14 and the interconnecting exhaust passages 15 (Figs. 1 and 2).

The valve 16 may be of any suitable form but herein the same is of the piston type having alternating spaced or circumferential grooves or shoulders, the said grooves being adapted, according to the position of the valve, to connect as desired the various pressure passages of the tool. The valve 16 works within the suitably apertured valve bushing 17, the end of which is closed by the threaded valve cap 18, the latter having the plug or stem 19 entering the hollow or tubular interior of the valve and acting as a guide and support upon which the valve is adapted reciprocatively to slide. The valve has a reduced closed end working within a constant pressure chamber 20, the latter connected by the passage 21 (Figs. 1 and 5) with the admission passage 14, so that the valve is constantly pressed toward the cap 18, but may be intermittently moved in the opposite direction and to the position shown in Fig. 1 by the intermittent admission of the pressure-fluid to the larger pressure receiving area at the opposite end of the valve between the same and the cap 18, which admission takes place under the control of one or the other of the two hammer-pistons through one or the other of the intermittent pressure ports 22 and 23 (Figs. 2 and 5).

In one position of the valve pressure is admitted to the head end of one cylinder and the tool or forward end of the other cylinder, while, at the same time, the head end of the second cylinder and the tool end

of the first cylinder are simultaneously opened to the exhaust. On reverse movement of the valve, which movement is effected by the connection of one of the intermittent pressure ports 22 or 23 with a live or constant pressure passage, reverse connections between the admission and exhaust and the respective ends of the cylinders are effected which simultaneously reverse the movements of the two pistons.

For the admission of pressure to and its exhaust from the head end of the cylinders, the cylinder 1 is provided with the passage 24 leading to the head end of the cylinder and controlled by the controlling valve 16, and the cylinder 2 is provided with a like passage 25. The passage 24 leads into an annular groove 26 (see Figs. 1 and 7) in the valve bushing 17, and the passage 25 to a similar annular groove 27, and the valve is also provided with co-operating circumferential grooves 28 and 29 through which the said passages are adapted alternately to be placed in communication with the pressure admission passage 14 as the valve is alternately moved from one position to the other. Next adjacent the grooves 26 and 27 respectively the valve bushing 17 is also provided with grooves 30 and 31, which, as shown in Fig. 1, connect directly and constantly with the exhaust passage 15, so that, with the valve in the position shown in Fig. 1, when pressure is being admitted to the head end of the cylinder 1, it is being simultaneously exhausted from the head end of the cylinder 2 through the passage 25, valve groove 29, bushing groove 31 and exhaust passage 15. In the reverse position of the valve, the head end of the cylinder 1 is connected with the exhaust through the passage 24, valve groove 28 and bushing groove 30.

The admission of pressure to and exhaust from the opposite or tool-end of the cylinders 1 and 2 is controlled through the tool-end pressure passages 32 and 33 respectively which, as represented in Figs. 2, 5 and 6, extend longitudinally in the walls of the cylinder casting between the piston chambers and enter their respective cylinders through the ports 34 and 35 at the lower ends thereof. The tool-end pressure passages 32 and 33 extend upward through the cylinder head and valve block (see Figs. 2, 5 and 7) where they have direct connection with the annular grooves 27 and 26 respectively by one or more horizontal passages 36 and 37 (see Figs. 5 and 7), so that, when the passage 24 is opened to the admission passage 14 by the valve 16, the tool-end pressure passage 33 for the tool-end of the other cylinder is simultaneously opened to the admission, and, when the passage 24 is opened to the exhaust, pressure fluid is simultaneously exhausted from the tool-end

of the opposite cylinder. In other words, the pressure controlling passage for the tool-end of each cylinder is so associated with the passage for the head end of the other cylinder that reverse pressure conditions invariably prevail at the corresponding ends of the two cylinders during operation of the instrument, thereby insuring the movement of the two hammer pistons in opposed step.

In the operation of a tool of this type it may frequently become desirable, for reasons which in one specific case are hereinafter more fully referred to, to throw out of operation one of the two hammer-tools while continuing to operate the remaining one. To provide such a control for the disclosed device I have shown the same equipped with suitable regulating means, herein in the form of a regulating valve 38, which is interposed between the controlling valve 16 and the two cylinders to control the several passages described, and thereby control the relative operation of the two tools. The details of this regulating valve will be more fully described, but its relation to the valve-reversing passages must now be referred to. Any desired means may be employed for connecting the intermittent pressure passages with a source of live pressure so as periodically to reverse the controlling valve, but in the present instance I have provided constant pressure passages 39 and 40 for the cylinders 1 and 2 respectively, which is each similar in arrangement to the constant pressure passage ordinarily employed in single piston tools of this type. That is to say, the constant pressure passage 39 opens into the cylinder 1 through a port 41 (Figs. 2 and 6), and the passage 40 into the cylinder 2 through a port 42, the ports 41 and 42 being located respectively at or about the same position lengthwise the cylinders as the two ports 43 and 44 which open from the intermittent pressure passages 22 and 23 into the cylinders 1 and 2 respectively. The pistons 6 and 7 being provided with the respective necked-down or reduced portions 45 and 46, the intermittent pressure port 43 would ordinarily be opened to live pressure through the constant pressure passage 41 when the piston 6 approaches the limit of its downward movement in the cylinder 1, and, on the other hand, the intermittent pressure port 44 would be placed in communication with the constant pressure port 43 when the other piston 7 approaches the limit of its downward movement.

When the cutting units are operated together as described the constant pressure and intermittent pressure passages of one cylinder are preferably closed by means of the regulating valve 38, as will more fully appear, and the reversal of the controlling valve 16 is effected by pressure received through the constant and intermittent pressure passages of the other cylinder,—herein the passages 23 and 40 of the cylinder 2, although the passages of the other cylinder might be employed equally well if desired. In order to exhaust the pressure from the larger differential area of the valve to reverse the latter, any suitable means may be employed, but herein, as is usual in tools of this class, the intermittent pressure passages, in addition to the ports 43 and 44, are also provided respectively with ports 47 and 48 (Fig. 2) opening into their respective cylinders at a point or level below or in advance of the ports 43 and 44, and also herein with additional ports 49 and 50 respectively still farther advanced.

Considering the simultaneous operation of the tools under the conditions referred to, that is to say, with the passages 23 and 40 open and the passages 22 and 39 closed, pressure would be admitted through the intermittent pressure port 44 to the larger differential area of the valve near the end of the forward movement of the piston 7 (as represented in Fig. 1), thereby reversing the valve and reversing the movement of the piston in each tool. On rearward movement of the piston 7 the port 48 in the intermittent pressure passage 23 is soon uncovered and the forward end of the cylinder 2, at that time being open to the exhaust (as will be explained), the pressure will be exhausted from the differential area of the valve and the latter reversed to reverse the movements of the two pistons. The additional ports 49 and 50 opening from the intermittent pressure passages, of which ports there may be a still greater number, provide means for varying the length of the hammer stroke by varying the instant when, during the backward stroke of the piston, the intermittent pressure passage is open to the exhaust. In place of this arrangement of auxiliary ports any suitable means may be utilized for this purpose, and, in conjunction with the described ports, any means for controlling the same may be used. In the present instance I have shown short slide rods 51 and 52 arranged within an extension of the intermittent pressure passages 22 and 23 respectively, with their upper ends adapted to act in the capacity of valves to open or close the intermittent pressure ports and thereby render the ports 49 and 50 effective or ineffective at will. When the hammers are worked together, if the slide rod 52 is lowered to uncover the port 50 the stroke of the tools is shortened, since the valve is reversed early in the stroke. To adjust the slide rods, the latter are encircled by spring clips 53 and 54, which project out through narrow slots 55 and 56 cut in the walls of the cylinder, so that the clips may be pinched together by hand and the rods raised or lowered.

ered. The clips when released spring outwardly against the walls of the slot and bind the rods in place.

The forward or tool ends of the cylinders 5 may be exhausted in any suitable way, but herein, as is customary in this type of tool, the forward cylinder ends are open to the exhaust through the uncovering by their respective pistons of an appropriately located 10 exhaust port or ports. The cylinder 1 is provided with a pair of exhaust ports 57, and the cylinder 2 with ports 58, the former connected to exhaust passages 59 and the latter to exhaust passages 60, which passages 15 extend lengthwise the cylinder casting 3 and the valve block but outside of the control of the regulating valve 38 and the controlling valves 16. At their upper ends these exhaust passages connect through grooves 61 and 62 20 (see Fig. 1) in the top of the valve block with the exhaust passages 15.

Since the arrangement of the various pressure passages relatively to the valve chamber and the cylinders for obvious constructional reasons are not completely shown in any one of the constructional views (Figs. 1-11 inclusive), there is shown in Figs. 12-15 a diagrammatic arrangement of these passages in the form of a development thereof, without attempting to portray accurately the mechanical construction which, however, is faithfully shown in the preceding figures referred to.

The operation of the described tool in the 35 light of the description already given will be clear from a consideration of Figs. 12-15. When it is desired to operate the tools simultaneously the regulating valve 38 is positioned as depicted in Fig. 12 closing the intermittent pressure passage 22 and the constant pressure passage 39 leading to the cylinder 1, while leaving open the head end pressure passages 24 and 25 and the tool-end passages 32 and 33 for the two cylinders, as 40 well as the intermittent pressure passage 23 and the constant pressure passage 40 for the cylinder 2. Under the conditions represented in Fig. 12 the piston 7 is at the forward end of its stroke, having delivered its 45 blow to the tool 9. The reduced piston portion 46 has already opened the intermittent pressure port 44 to the constant pressure port 42 and the resultant access of pressure to the larger differential area of the valve 50 through the passage 23 has reversed the position of the valve. This has caused the opening of the head end of the cylinder 2 to the exhaust passage 15 through the passage 25, the opening of the forward end of the cylinder 2 through the port 35 and the passage 33 to the admission passage 14, and, in the cylinder 1, the opening of the head end passage 24 to the admission and the tool-end passage 32 through its port 34 to the exhaust, 55 the direction of transference of pressure

fluid being represented by arrow heads appearing in the said figure. On the subsequent and resulting upward stroke of the piston 7, which is accompanied by a simultaneous downward stroke of the piston 6, the 70 exhaust port 58 is soon uncovered and followed directly afterward by the opening of the intermittent pressure port 48, thereby exhausting pressure from the larger differential area of the valve, causing the constant 75 pressure at the opposite end of the valve to reverse the same, as represented in Fig. 13, when pressure is admitted to the head end of the cylinder 2 and to the tool end of the cylinder 1, as depicted in Fig. 13, acting to 80 drive the piston 7 down and the piston 6 up. It will be seen that this arrangement enforces the non-synchronous and out-of-step operation of the two tool units, causing each to counteract to some extent the shock or 85 impact of the other with reference to its effect upon the contained casing, although, of course, without in any way affecting or decreasing the effectiveness of the hammer blow of each tool. If it is desired to throw both cutting units out of operation, the regulating valve 38 may be turned to the position represented in Fig. 14 where the intermittent pressure passage 23 and the constant pressure passage 40 of the cylinder 2 90 are closed, as is also the pressure passage 25 and the tool end pressure passage 33 for the cylinder 2. In this position of the regulating valve, the controlling valve 16 will move to the position shown in Fig. 12 and there 100 remain, for the hammer 6 after concluding its forward stroke will then admit pressure fluid through the intermittent pressure passage 22 to the large area of the controlling valve maintaining the latter in the position assumed (Fig. 12) and stopping further movement of both pistons until the regulating valve is again turned back. On the other hand, if it is desired to operate the hammer piston 7 alone the regulating valve 38 may 105 then be turned to provide for the conditions represented in Fig. 15, where the several pressure passages 22, 39, 24 and 32 leading to the cylinder are closed, while the corresponding passages leading to the cylinder 110 2 are held open, thereby throwing out of operation the piston 6 within the cylinder 1, while causing the sole operation of the piston 7 within the cylinder 2 as a single tool. Under such conditions the valve 16 is moved 115 to the position shown in Fig. 12 by admission of pressure from the constant pressure port 42 to the intermittent pressure port 44 on the forward movement of the piston 7, but again returns to its initial position as 120 shown in Fig. 13 on the upward movement of said piston, as soon as the port 48 is uncovered to the exhaust and the pressure-fluid exhausted from the larger differential 125 area of the valve. 130

The regulating valve 38 may be of any suitable construction and located in any selected position on the tool, but herein I have constructed the same as represented in Figs. 8-11 and arranged the same transversely 5 the tool beneath the valve 16 as represented in Fig. 2. The valve as shown is provided with two piston or barrel portions 63 and 64 connected by an intermediate flat portion 65. The latter lies adjacent the passages 24 and 25 in the valve block, as best shown in Figs. 1-4, so that in one position the said 10 passages are both left free and open (Fig. 1), in another the passage 24 maintained closed and passage 25 open (Fig. 3) and in the third position the passage 25 closed and the passage 24 open. The barrel portion 63 is provided with apertures 66, 67 and 68 which, with the valve in position, align with 15 the passages 23, 32 and 39 respectively. The barrel portion 64 likewise is provided with apertures 69, 70 and 71, which with the valve in position, are adapted to align with the passages 22, 33 and 40 respectively. The 20 shape of the apertures 66 and 71 is shown in Fig. 9, the shape of the aperture 70 in Fig. 10, and the shape of the apertures 67, 68 and 69 in Fig. 11. This valve formed as disclosed provides for the desired regulation 25 of the pressure passages, which has been described with reference to Figs. 12, 14 and 15. The end of the barrel portion of the valve 64 is provided with a projection 72 (Figs. 2 and 8), which is embraced by the forked 30 end of the valve stem 73, the latter passing through an aperture in the threaded cap 74 (Figs. 2 and 16), and provided with the external regulating lever 75. The lever is 35 provided with a thumb or finger piece 76 carrying a sliding spring-pressed pin 77 adapted to engage with any one of three notches formed in the exterior face of the 40 valve block (Fig. 16), whereby it may be moved to a central position represented in Figs. 2 and 12, or to a position against the stop 78 to throw out of operation both cylinders (Fig. 14), or against the oppositely disposed stop 79 to throw out of operation 45 the cylinder 1 (Fig. 15), the spring-pressed pin 50 acting to retain it in its assigned position.

To better understand the utility of the described tool reference may be had to Figs. 17 and 18 which show one specific application of a tool of this type, herein specifically for the purpose of surfacing or dressing stone. This application of the tool is illustrative only as to the principal features of novelty of my invention, the latter being obviously applicable to numerous other purposes widely different from the one herein suggested and shown.

In the use of a multiplex tool such as described and particularly in conjunction with 65 the control which provides for the joint or

sole operation of these tools at will, it may oftentimes be desirable to turn the tool freely and at will, thereby to direct the action of either individual tool accurately and effectively with reference to the work. For 70 example, in its application to a stone surfacing machine, where the tool is supported upon a suitably adjustable overhead support, it becomes a matter of importance to turn the duplex tool freely when operated 75 jointly to maintain the cuts in desired alignment. When it is cutting along the edges of the block, it will often be desirable to throw one of the tool-actuating units out of operation to avoid breaking the edges, while 80 still having means at the same time to turn the tool as a whole to better direct and control the action of the then operative units.

In order that the tool-actuating device described may be readily turned within its 85 holder to suitably adjust or align the cutting tools, I have provided the instrument with a swivel support in its holder, which latter herein is represented (Fig. 17) by the adjustable tool carriage 80 of a stone working 90 machine. For this swivel support I have provided the end piece 13 with a tubular extension 81 which is supported for rotatable movement within the sleeve 82 formed upon the carriage and preferably upon the 95 ball bearings 83, whereby the instrument may be turned at will during its operation. The upper end of the tubular member 81 has suitable connection through the nipple 84 with the source of fluid pressure supply 100 (the latter not shown) and interposed between the latter and the nipple is provided a suitable form of throttle valve 85 (Fig. 18) by which the admission of pressure may be controlled and the operation of both tool-actuating units stopped at any desired time. The end piece 13 is provided with lugs 86 through which pass the bolts 87, the latter at their opposite ends also passing through the lower end piece 5 and acting to clamp 110 between the latter and the end piece 13 the cylinder casting and valve block. As a convenient means for locking in the threaded valve cap 18 the head of the latter (Figs. 1 and 5) is cut with a plurality of transverse 115 grooves 88 within one of which the adjacent bolt 87 is adapted to lie when the parts are assembled. This obviously prevents the turning of the valve cap until the bolts are taken out and the parts separated, when the 120 valve cap may be again turned.

In order to provide means for turning the instrument about its swiveled support the former is provided with a handle 89 (Fig. 5) which (Fig. 1) encircles and is bolted at 125 either side of the lower end of the cylinder casting to a plate 90, the latter fitting into a recess formed in the casting.

In the particular application of the instrument to a stone surfacing machine as 130

represented in Figs. 17 and 18, the tool-holding carriage 80 is provided with suitable rollers 91 adapted to travel along the radial supporting arm 92, the latter comprising a pair of suitably joined track-forming members, the handle 93 being provided on the carriage to adjust the tool-holding carriage along the arm. The arm 92 receives support from a central carrier or holder 94, the latter being slidably mounted upon the upright supporting standard 95 as by the barrel piece 96 shown, so that the carrier may be adjusted vertically to any desired height. The vertical adjustment of the carrier may be effected in any suitable way as by the rope or cable 97 which passes upward over the overhead sheaves 98, thence downward to a position where it is accessible to the operator. The carrier 96 has swivel attachment to the column so that the operator by moving the carriage may swing the latter with its arm through the arc of a circle, and, in addition to the radial adjustment of the tool carriage itself along the arm, the latter may be adjusted longitudinally within the carrier and upon the rollers 99 and clamped or held in its adjusted position by any suitable means. In its operation, therefore, the tool upon its carriage may be moved to any position over the surface of the underlying block of stone and the instrument turned radially upon its axis, while, at the same time, the regulating valve, as described, may be utilized to so govern the action of the instrument as to actuate the tool-actuating units either jointly or solely.

I have described the action of the disclosed duplex hammer tool in detail with reference to its use upon a stone surfacing machine in order that the mode of operation may be more fully understood and the co-ordination between the various elements of control more easily comprehended. My invention as herein described and hereinafter more broadly claimed is limited to no particular application or use.

It will be obvious that a duplex or other multiplex tool may be employed, wherein the reciprocal or non-synchronous movement of the tool-actuating devices may be secured while employing more than a single valve-controlling means, and that with such a construction regulating means either similar to those described or other regulating devices for similar purposes may be employed for controlling the joint and sole action of the tool-actuating units. While such modifications are within the scope of my invention as herein claimed I preferably employ a single valve-controlling means, since it lends itself to simplicity of construction and certainty in operation.

While I have shown for illustrative purposes one embodiment of my invention, it is to be understood that the same is not limited

to the particular form herein disclosed or to the details of construction which, for the sake of explicitness are herein fully described and illustrated, but that extensive modifications and deviations from the illustrated construction may be made without departing from the true spirit of the invention.

Claims:

1. A pneumatic impact tool or hammer having a pair of piston-hammer members adapted to reciprocate each within its appropriate cylinder, suitably held tools adapted each to receive the impact of one of said hammer members, a single controlling valve for said hammer members having differential pressure areas, means for maintaining the smaller differential area of the valve constantly exposed to pressure fluid to press the valve constantly toward one position, suitable admission and exhaust passages, pressure-fluid passages controlled by the valve and leading to opposite ends of each cylinder, the valve in one position being adapted to connect the head end of one cylinder and the tool end of the other to the admission, and the tool end of the first cylinder and the head end of the other cylinder to the exhaust, and in its reverse position to effect reverse connections, said cylinders being each provided with a constant pressure passage and an intermittent pressure passage having ports opening into the cylinder at or about the same point and adapted to be placed in communication with each other on forward piston movement, thereby to admit pressure to the larger differential area of the valve, an exhaust port for the forward end of each cylinder adapted to be uncovered on rearward piston movement, a second port connecting each cylinder with its intermittent pressure passage and adapted to be uncovered by the rearward piston movement, thereby to exhaust the pressure-fluid from the larger differential area of the valve and to reverse the latter, and a regulating valve adapted to control the pressure passages of the two cylinders, said valve in one position being adapted to close the intermittent pressure passage and constant pressure passage of one cylinder, while leaving open the intermittent pressure passage and constant pressure passage of the other cylinder and also leaving open the pressure passages leading to the opposite ends of both cylinders, in another position additionally to close the pressure-fluid passages leading to the opposite ends of the first-mentioned cylinders and in still another position to open the intermittent pressure passage, constant pressure passage and cylinder pressure passages for said first-mentioned cylinder while closing the corresponding passages for said other cylinder.

2. A pneumatic impact tool or hammer

- having a pair of piston-hammer members adapted to reciprocate each within its appropriate cylinder, a separate actuated tool for each hammer member, a single controlling valve for said hammer members having differential pressure areas, means for maintaining pressure fluid upon the smaller differential area of the valve to press the latter constantly toward one position, fluid supply passages controlled by said valve to supply pressure fluid for moving the hammer members in opposite directions in one position of the valve and reversely in its reverse position, an intermittent pressure passage leading to each cylinder and communicating with the larger differential area of the valve, means for placing said passages in communication with a supply of pressure fluid on forward piston movement, and means at will for closing the intermittent pressure passage for one cylinder, thereby causing the joint operation of the hammer members in opposed step and the control of the valve through one hammer member or for cutting off the operative supply of pressure fluid to one cylinder at will, thereby to actuate a single hammer member only.
3. A pneumatic impact tool or hammer having a pair of piston-hammer members adapted to reciprocate each within its appropriate cylinder, separate actuated tools adapted to receive each the impact of one of said hammer members, a single controlling valve for admitting pressure fluid to cause said hammer members to move in opposed step, pressure fluid means for controlling the reversal of said valve through piston movement, and pressure fluid regulating means for withholding operative pressure fluid from one cylinder while continuing to supply the other thereby to throw out of operation one of said piston-hammers at will while continuing the operation of the other.
4. A pneumatic impact tool or hammer having a pair of piston-hammer members adapted to reciprocate each within its appropriate cylinder, a single controlling valve therefor, a pressure fluid passage for each cylinder adapted to be controlled by its respective piston for the passage of pressure fluid to reverse the valve, pressure fluid regulating means to close one of said pressure passages at will, and, at the same time, cut off the operative supply of pressure fluid to the corresponding cylinder, or to close one of said passages while maintaining the operative supply of pressure fluid to each cylinder, thereby to effect the sole operation of one of said hammer members or joint operation of said hammer members at will.
5. A pneumatic impact tool or hammer having a pair of piston-hammers adapted to reciprocate each within its appropriate cylinder, a single pressure-actuated controlling valve to cause said piston-hammers normally to reciprocate in opposed step, and valve means for withholding effective power from one of said hammers while continuing to supply the other thereby to throw out of operation one of said hammer members at will, while continuing the operation of the remaining one.
6. A pneumatic impact tool or hammer having a pair of piston-hammer members adapted to reciprocate each within its appropriate cylinder, a single valve for controlling said members and causing their reciprocation in opposed step, and valve means for withholding effective power from one of said members while continuing to supply the other thereby to throw out of operation one of said hammer members at will while continuing the operation of the remaining one.
7. A pneumatic impact tool or hammer having a pair of piston-hammer members adapted to reciprocate each within its appropriate cylinder, a single controlling valve, and valve means for withholding effective power from one of said members while continuing to supply the other thereby to throw out of operation one of said hammer members at will, while continuing the operation of the remaining one.
8. A pressure-fluid tool-actuating device having a plurality of tool-actuating units adapted to reciprocate non-synchronously, a single controlling valve for controlling the reciprocation of said units, and means for withholding effective power from one of said units while continuing to supply the other thereby to throw one of said units out of operation at will.
9. A pressure-fluid tool-actuating device having a plurality of tool-actuating units, a single pressure-fluid-controlled valve for controlling the reciprocation of said tool-actuating units, and valve means for directing the pressure fluid to one or the other of said units thereby to operate said units jointly or for throwing one out of operation at will, while continuing the operation of the remaining one.
10. A pneumatic impact tool or hammer having a plurality of hammer members, means for applying power for operating said members to cause said hammer members to operate jointly in opposed step and means to withhold effective power from one of said members, while continuing the supply to the other thereby to throw one of said members out of operation at will, while continuing the operation of the remaining member.
11. A pneumatic impact tool or hammer having a plurality of hammer members, a single controlling valve for the same, and means at will to operate said hammer members either together or one alone.

12. A pneumatic impact tool or hammer having a pair of piston hammer members and provided with a live pressure-fluid supply source and exhaust passages, and a 5 single automatically-acting manually-controllable means for connecting opposite sides of each piston hammer member alternately with the live pressure fluid supply and the exhaust passages to cause reciprocal 10 movement of said hammer members.
13. A pneumatic impact tool or hammer having a plurality of piston hammer members and provided with a live pressure fluid supply source and exhaust passages and a 15 single automatically-acting manually-controllable means for connecting opposite sides of each of said piston hammer members alternately with the live pressure fluid supply and the exhaust passages for causing an 20 out of step reciprocation of said hammer members.
14. A pneumatic impact tool or hammer having a plurality of hammer members, an actuated tool for each hammer member, 25 means for applying power to both of said members thereby to provide for the operation of said hammer members jointly, and means to withhold effective power from one while continuing to supply the other for 30 the sole operation of one of said hammer members at will.
15. A pneumatic impact tool or hammer having a pair of piston-hammer members, separate actuated tools adapted to receive 35 each the impact of one of said hammer members, means for supplying power to both of said members to cause their joint operation and means to withhold effective power from one while continuing to supply the other for 40 throwing out of operation one of said hammer members at will.
16. A duplex pneumatic impact tool or hammer having a pair of cylinders and a pair of piston-hammer members, a differential pressure-actuated valve for controlling the same, an intermittent pressure passage opening into each cylinder and adapted to be placed in communication with pressure fluid on the forward movement of the piston 45 to admit pressure thereto and thereby reverse the valve, an exhaust port adapted to be uncovered on rearward movement of the piston, a plurality of ports opening into said intermittent pressure passage and adapted 50 to be placed one or another in communication with the said exhaust port on the rearward movement of the piston, and manually operable valve means for rendering one of said intermittent pressure ports effective or 55 ineffective at will.
17. A pneumatic hammer having a valve chamber, a threaded plug closing the end of said valve chamber, and a tie-rod for said 60 hammer, said plug having a suitably recessed head adapted when the parts are assembled to be engaged by said rod and thereby locked in threaded engagement with the hammer.
18. A pneumatic hammer having a valve chamber, a threaded plug closing the end thereof, an exteriorly grooved head for said plug, and a member upon said hammer adapted when the parts are assembled to engage a groove in said head, thereby to lock said plug in position.
19. The combination with a pair of cylinders of reciprocatory tool actuating members, one in each cylinder, separate actuated tools adapted to be actuated each by one of said members, a single controlling valve for 80 admitting pressure fluid to move said members in opposed step, pressure fluid means for controlling the reversal of said valve through piston movement and manually operable fluid regulating means for throwing 85 out of operation one of said members at will while continuing the operation of the other.
20. The combination with a pair of piston members adapted to reciprocate each within 90 its appropriate cylinder, a single valve for controlling said members and causing their reciprocation in opposed step and manually operable valve means for throwing out of operation one of said members at will while 95 continuing the operation of the remaining one.
21. The combination with a plurality of tool actuating units adapted to reciprocate non-synchronously, of a single controlling 100 valve for controlling the reciprocation of said units and manually operable valve means for throwing one of said units out of operation at will.
22. The combination with a plurality of 105 tool actuating units of a single pressure fluid controlled valve for controlling their reciprocation and manually operable valve means for operating said units jointly or for throwing one out of operation at will 110 while continuing the operation of the remaining one.
23. The combination with a plurality of reciprocatory tool actuating members of a single controlling valve for the same and 115 means for withholding operative fluid from one while continuing to supply the other thereby to operate said members either together or one alone.
- In testimony whereof, I have signed my 120 name to this specification, in the presence of two subscribing witnesses.
- GEORGE H. GILMAN.
